 TREATMENT OF HUMAN DERMATOSES WITH
DIBENZOTHIOPHENE

Josef Vonkennel, Cologne, Germany, assignor, by mesne assignments, to Helena Rubinstein, Inc., New York, N.Y., a corporation of New York
No Drawing. Filed Oct. 12, 1959, Ser. No. 845,649
3 Claims. (Cl. 167—58)

The present invention relates to the treatment of human skin disorders.

It has been found in accordance with the present invention that dibenzothiophene is highly therapeutic in the treatment of skin disorders. This compound which is known also as di- or biphenylene sulphide has the following graphic formula

This compound is available, as for example from Farbenfabriken Bayer Leverkusen in West Germany, and can be made by any one of the following processes:

(1) Heat a mixture of diphenyl, sulfur and aluminum chloride at a temperature of 110° C.—115° C. The reaction proceeds with the generation of hydrogen sulfide. After 8—10 hours, the temperature is increased to 230° C.—240° C. The dibenzothiophene is obtained with a yield of 80% by distillation. The material can be purified by crystallization from ethyl alcohol.

(2) Boil diphenylene sulfoxide with sodium or potassium amide.

(3) Heat dioxy-diphenyl with phosphorus pentasulfide.

(4) Heat diphenylene disulfide with copper at 250° C.

The compound has a melting point of 96°—98° C., a boiling point of 332°—333° C. and a sulfur content of approximately 17.3%.

It has been found in accordance with the present invention that dibenzothiophene is especially effective in the treatment of such skin afflictions as acne, seborrhea, and related dermatoses of the pilo-sebaceous system. In the treatment of such skin disorders, the dibenzothiophene besides its high curative properties, is anti-inflammatory, is disinfecting and promotes normal keratinization.

Also, dibenzothiophene, due to its high degree of compatibility, lends itself admirably to compounding in the preparation of stable creams and lotions, and may be incorporated into cosmetic powders, such as compact face powders, to be employed not only as a medicinal product but also as a cosmetic one. Dibenzothiophene has little or no odor, so that blending with cosmetic bases with pleasant fragrant effects can be easily achieved.

It has been found in accordance with the present invention, that preparations containing dibenzothiophene in concentrations of as low as 1% by weight are therapeutically effective for healing skin disorders. Dibenzothiophene can be employed in high concentrations, since it can be tolerated by human beings without side effects. However, for practical purposes, the concentration should not exceed 10%. A preferred concentration of dibenzothiophene is about 5% by weight.

Example 1

A specific example of a formulation for a cream is as follows:

	Grams
Lanogen C	8.0
Lanette O	4.0
Olive oil	8.0
Cetiol V	8.0
Comperlan 100	3.0
Dibenzothiophene	5.0

2

Water	48.0
Sorbitol 70% sol.	4.2
Vitamin oil soap	12.0
Perfume	1.0
5 Mercuric sulfide	0.125
Tegosept "M"	0.1
Tegosept "P"	0.2
	101.6

In the above formulation, the vitamin oil soap has the composition

	Grams
Vitamin oil	360
50% sol. of KOH	162
Water	42
Alcohol	36

The ingredients in the above formulation have the following general description

- 20 Lanogen C—emulsifying agent manufactured by Anorgana, G.m.b.H., Gendorf, Upper Bavaria. This is a mixture of various fatty and wax alcohols, obtained by hydrogenation under high pressure of natural raw materials. The mixture is modified by introduction of polyether groups.
25 Lanette O—mixture of higher saturated animal fatty alcohols, mostly cetyl and stearyl alcohols. Manufactured by Deutsche Hydrierwerke, Dusseldorf.
30 Cetiol V—mostly oleyesters of oleic acid. Manufactured by Deutsche Hydrierwerke.
Comperlan 100—a fatty acid amide. Manufactured by Deutsche Hydrierwerke.
Vitamin oil—an oil obtained mostly from corn germs.
35 Manufactured by Keimdiat, G.m.b.H., Augsburg.
Tegosept "M"—methyl-p-hydroxybenzoate.
Tegosept "P"—propyl-p-hydroxybenzoate.

In the above formulation of Example 1, the active therapeutic ingredient is dibenzothiophene. The Tegosept "M" and Tegosept "P" inhibit bacterial and fungicidal growth in the cream and, therefore, are preservatives for the cream. The Lanogen C, Lanette O, Cetiol V and Comperlan 100 are emulsifiers for the cream and along with the olive oil, sorbitol, vitamin, vitamin oil soap have a soothing effect on the skin. The mercuric sulfide imparts a pink tint to the composition and therefore enhances its pleasing appearance and causes the composition to blend with the color of the skin. This mercuric sulfide can be dispensed with or replaced by other types of tinting agents.

50 *Method of preparation.*—The vitamin oil soap can be prepared as follows: Mix the vitamin oil with the alcohol and add the solution of KOH, stirring very well. The heat developed in a batch of 5 kilos is so great that no additional heating is necessary. The soap is then dissolved in distilled water.

55 The main composition is prepared as follows: The necessary quantity of vitamin oil soap, i.e., 12 grams, freshly prepared as described, is dissolved by heat in $\frac{2}{3}$ of the quantity of water prescribed for the formulation 60 of Example 1, i.e., 32 grams. Any water lost by evaporation during this procedure is replenished. To the mixture of vitamin oil soap and water formed, there is added the solution of sorbitol and after the Tegosept "M" has been added, the resulting admixture is heated up to 60° C. and will constitute the water phase referred to hereinafter.

65 Lanogen C, Lanette O, olive oil, Cetiol V, Comperlan 100 and the dibenzothiophene are brought together and heated up to 60° C. to form a melted mixture. The mercuric sulfide is triturated with a little of this melted mixture and added to the bulk of the melted mixture and the Tegosept "P" is added. The waxes produced by

this procedure are added slowly to the water phase prepared as described above and the admixture is stirred. The balance of water (16 grams) is added to this admixture as soon as it has cooled off and perfume is added at 30° C. The resulting admixture is then homogenized.

The cream produced by the above formula is stable, nongreasy, readily absorbable, and easily washable, has a pleasant odor and has good cosmetic properties. It has been found to be safe and efficacious in the treatment of skin disorders, and especially those listed above.

In the use of the preparation, the affected skin areas are washed thoroughly and a thin film of the preparation is applied during the day and before bedtime without rubbing and primarily to the areas affected. This mode of application is continued every day and at every bedtime until the skin disorder is corrected.

Example 2

The dibenzothiophene can also be incorporated into a liquid base to form a lotion. The formulation for this lotion is as follows:

	Grams
Dibenzothiophene	5.0
Glycerin U.S.P.	5.0
Hexachlorophene	0.5
Alcohol (40 M)	8.0
12% suspension of bentonite, U.S.P., in water	12.5
Titanium dioxide, cosmetic grade	5.9
Zinc oxide U.S.P.	3.15
Red oxide	0.5
Yellow iron oxide	0.5
Perfume	0.25
10% solution of Cellosize WP-09 in water	58.7
	100.0

In the above formulation, Cellosize is hydroxyethylcellulose.

In the formulation of Example 2, the dibenzothiophene is the active medicinal ingredient. The hexachlorophene serves as a mild antiseptic. The alcohol and bentonite have an astringent, drying effect. The titanium dioxide, red oxide, and yellow iron oxide are pigments to impart to the lotion a flesh tint. The Cellosize controls viscosity and aids in stabilizing the suspension. The zinc oxide is an additional medicament.

Method of Preparation.—In the compounding of the lotion of Example 2, the following procedure is followed.

- (1) Prepare a suspension of Bentonite, U.S.P., in water.
- (2) Prepare a solution of Cellosize in water.
- (3) Dissolve the perfume and the hexachlorophene in the alcohol.
- (4) Mix the titanium dioxide, zinc oxide, red oxide and yellow iron oxide together with the dibenzothiophene and micronize.

The preparations of the different steps are brought together as follows:

Mix together glycerin and the bentonite suspension of step 1 and add to the resulting mixture the alcohol solution of perfume and hexachlorophene. Mix in the micronized powders of step 4 and add gradually under continuous mixing, the Cellosize solution. Homogenize the resulting admixture.

The lotion produced by the formulation of Example 2 is a stable, pleasant smelling, cosmetically acceptable preparation, which can be dispensed conveniently from a plastic squeeze bottle or from a glass bottle. The lotion can be applied in the manner described in connection with the formulation of Example 1, and is safe and highly efficacious for skin disorders, especially for those of the character described.

Example 3

The dibenzothiophene lends itself admirably to incorporation into various desirable cosmetic bases having good compatibility for use by women in the daytime, as in the manner of ordinary cosmetics, to form a composi-

tion serving as a combined cosmetic and medicinal preparation. For example, the dibenzothiophene can be incorporated into a cosmetic powder base having the following formulation.

	Parts by weight
Zinc stearate	11.2
Zinc oxide	11.2
Talc	63.0
Kaolin	12.4
10 Mineral oil	2.2
	100

With the above formulation is incorporated either one of the following flesh colored pigments according to the shade desired.

	Grams
For light shade:	
Yellow pigment	550
Red pigment	450
For dark shade:	
Yellow pigment	1850
Red pigment	600
Red-brown pigment	200

25 The above amounts of pigments are calculated for 97.8 kilos of the powder mixture consisting of zinc stearate, zinc oxide, talc and kaolin. The pigments may be procured, for example, from Feuerbach, West Germany.

Method of preparation.—In the preparation of the formulation for the dibenzothiophene with the cosmetic powder base, the powders consisting of the zinc stearate, zinc oxide, talc and kaolin are mixed together, the pigments are added and the resulting mixture is stirred thoroughly for mixing. To 97.8 kilos of the powder mixture to which the pigments in the amounts indicated have been added, there is thoroughly admixed 2.2 kilos of mineral oil. The dibenzothiophene is micronized, put through a sieve and added to the finished powder mixture in the proportions of 5 parts of dibenzothiophene to 95 parts of the powder mixture. If necessary, the finished product may be put through a sieve and pressed into the form of a compact face powder.

30 The powder may be applied to the face or other exposed parts of a woman's afflicted skin as in the manner of ordinary cosmetic or face powder, such as compact face powder. The powder is applied every day until the skin disorder has been cured.

35 While the invention has been described with particular reference to specific embodiments, it is to be understood that it is not to be limited thereto but is to be construed broadly and restricted solely by the scope of the appended claims.

40 What is claimed is:

1. The process of treating acne, seborrhea and related dermatoses of the pilo-sebaceous system, which comprises applying to the affected skin areas a preparation containing dibenzothiophene as the curative agent.
2. The process of treating acne, seborrhea and related dermatoses of the pilo-sebaceous system, which comprises applying to the affected skin areas a preparation containing dibenzothiophene in the amount of the least 1% as the effective curative agent.
3. The process of treating acne, seborrhea and related dermatoses of the pilo-sebaceous system, which comprises applying to the affected skin areas a preparation containing dibenzothiophene in the amount of about 5% as the effective curative agent.
